UNITED STATES PATENT OFFICE

RICHARD W. RIGLER, OF PHILADELPHIA, PENNSYLVANIA

CENTRIFUGAL DRIER

Application filed July 18, 1930. Serial No. 468,949.

The invention relates to centrifugal driers, and to means associated therewith for purging, washing or bleaching and drying, adapted for use with coal, chemical salts, sugar, paper pulp, grains, sewage and other material.

An object of the invention is to insure continuous operation, so that the material being treated enters and is automatically discharged from the apparatus in a continuous stream without periodical interruptions or stopping or reducing the speed of the machine.

Another object is to provide a method and means to cause the material being treated as fed to the machine to gradually pick up speed as it is being treated, thereby resulting in a saving of power for rotating the drier, avoiding injury or breaking up of fragile crystalline products being treated, and doing away with shocks, jars or vibrations to the machine due to material being treated being caused to too quickly pick up the speed of the drier.

As will be more fully explained herein-after, the apparatus includes the customary rotary hollow screen or basket and a screw conveyor rotating coaxially with said basket in the same direction and in close proximity thereto but at a slightly different speed. To obtain these differential speeds there has been employed in the past a countershaft, connected to the respective spindles or shafts by spur, bevel, or spiral gears which have not been satisfactory for the following reasons: The gears mounted on the main drive shafts rotate in a counter direction to their meshing gears on the countershaft and due to the rapidity of rotation, the teeth of the gears engage and impinge at very high peripheral speeds. Therefore extreme accuracy must be exercised in the manufacture to insure perfect alignment, as otherwise uneven pressure will result upon the few teeth that are engaged or in contact, and constant lubrication must be applied to the teeth, in spite of which the rotation of the gears is accompanied with considerable noise and consequent vibration. This type of drive is

also unsymmetrical to the general design of the machine.

Another object of the invention is to provide gearing that shall rotate noiselessly in the same direction, coaxially in pairs, and considerably reducing the speed at which the teeth of the gears engage; providing a greater number of teeth in contact, thereby decreasing the unit tooth pressure; avoiding necessity for lubrication to any extent; increasing the efficiency of the drive and making the drive symmetrical to the general design of the machine; obtaining a greater number of tooth combinations, thereby affording a greater number of differential speeds of the rotary hollow screen or basket and the screw conveyor, and retaining the straight face or radial teeth of the spur gear type.

Another object is to automatically clean the perforations of the rotary screen, thereby insuring continuous operation and avoiding stoppages for cleaning purposes.

Another object is to provide means to take up or compensate for the stresses and strains or vibrations of the screen basket and screw conveyor owing to centrifugal movement thereof, and to uneven distribution of the material being treated due in part to uneven feeding of the material and in part to uneven accumulation of the dried or partly dried material circumferentially of the screen basket.

Another object is to provide in connection with the drier a method and means for washing, purging or bleaching the material being treated, by the introduction of a suitable agent for this purpose while the drying operation is proceeding.

Another object of the invention is to provide means for evenly feeding the material to load the screen basket evenly of its circumferential surface.

The invention consists in the novel construction and combinations of parts and in the associated steps or procedure as herein-after set forth in the claims.

In the accompanying drawings illustrating an embodiment of the invention,

Fig. 1 is a central longitudinal section of the machine with parts in full lines.

Fig. 2 is a side elevation of the machine.

Fig. 3 is a detail top plan view of the gear case and differential gears.

Fig. 4 is a detail fragmentary composite sectional and side view of a modification.

Fig. 5 is a detail fragmentary section on the line 5—5, of Fig. 6.

Fig. 6 is a bottom plan view of a modification.

Fig. 7 is a detail section on the line 7—7 of Fig. 6, at the limit of outward movement.

In these drawings, the numeral 1 designates 15 an electric motor, the base of which is bolted to the housing 2, the motor shaft being coupled to center shaft 3 by coupling 4, preferably of the flexible type. The weight and thrust load upon said shaft 3 is supported by 20 bearing 5 including a nut 6 screwed on shaft 3. This center shaft has bearing 7 in the said housing wherein it freely rotates, and at its lower end said shaft is provided with the bottom 8, securely keyed and clamped up 25 against a shoulder of the shaft by a suitable nut. Surrounding the shaft 3 is a tubular shaft 9, having bushings 10 in each end bearing upon shaft 3.

To the lower end of tubular shaft 9 is secured 30 by a key, screw conveyor casting 11, having a clamping nut 12 under which is a suitable thrust bearing 13. The shaft 9 is rotatable in bearing 14 of the gear housing to be later described.

35 Cast integral and connected by the ribs or radial vanes projecting upwardly from the periphery of the bottom 8 for the rotary hollow screen or basket is the annular diffusion rim to the top of which is bolted the lower 40 flange 17 of the rotary hollow screen or basket 15. Secured to the top flange 19 of said hollow screen or basket is a frusto-conical end portion or top 16 which is also of screen material.

45 The rotary hollow screen 15 and its frusto-conical top 16 are constructed of perforated sheet metal rolled to form and reinforced by ring flanges 17, 18, 19, 20 and 21.

Both screen sections 15 and 16 are lined 50 with the customary filtering mediums, comprising finely perforated sheet metal 22, intervened with woven wire cloth, bolted or otherwise secured thereto.

55 The blades or flights of the screw conveyor 11 flare at an upward angle from the periphery of the cylindrical body thereof, the outer circumferential edges of said flights having a clearance space between the same and the inner circumferential surface of the rotary 60 screen lining 22.

Resting on top of the screw conveyor rim and hub 11 is a cast frusto-conical support 24, for the loading plate 25, both of these parts being suitably secured to the tubular shaft 9 65 to rotate therewith, and part 24 forming in

effect a frusto-conical end for the screw conveyor, spaced from the frusto-conical top or end 16 of the rotary hollow screen.

26 designates a rolled sheet metal monitor 70 case that is stationary and supported by the annular base 27 bolted thereon, said base having two sloping spiral troughs leading to two opposite liquor outlets.

Secured to the top flange of said monitor case is a sheet metal cover plate 28, having a suitable number of vent holes 29 and supporting a cast feed hopper 30. To facilitate removal for making replacements, the case 26, cover plate 28, and hopper 30 are made in 75 halves or sections.

Referring now to the gearing, 31 designates a spur gear of the ordinary variety, keyed to center shaft 3, and meshing with and driving internal spur gear 32. Directly below this pair of gears is a similar pair of 80 gears of larger diameter, the teeth of which are of the spur gear type, and of which outer internal gear 33 drives inner spur gear 34, the latter being mounted fast upon the upper end of tubular shaft 9. Internal gears 32 and 33 are both keyed or otherwise secured to the 85 inner side of the two-piece case or carrier 35.

As this case or carrier 35 rotates as a unit, upper and lower extensions 37' and 38' thereof are provided with bearings 37 and 38 in 90 the housing 2 and in the gear housing 40. The outer circumferential surfaces of both of these tubular extensions are machined concentrically with the internal gears 32 and 33,

and rotate about the center axis represented by the line II—II, Fig. 3, in said bearings 37 and 38, the latter being eccentric to the bearings 7 and 14 of the housing 2, and the housing 40, and wherein the shafts 3 and 9 rotate. This eccentricity causes center shaft 3 to be located eccentrically of the interior or bore of the upper hollow extension 37' of case 35, and tubular shaft 9 to be located similarly eccentrically of the bore of the lower tubular extensions 38'. Case 35 is provided with bearing support 39 upon gear housing 40.

The housing 2 for the bearings 7 and 37 and which supports the motor and the bearing 5 that carries the load of the center and tubular shafts 3 and 9, has its lower flange bolted to the flange of the gear housing 40.

In order to compensate for the stresses and strains or vibrations of the screen basket and screw conveyor, owing to centrifugal movement thereof and to uneven distribution of the material being treated, due in part to uneven feeding of the material and in part to uneven accumulation of the dried or partly dried material circumferentially of the screen basket, the gear housing 40, which has the bearing 38 for the lower tubular extension of said gear case and the bearing 14 for tubular shaft 9, and which bears the load of the housing 2, which latter has the bearing 37 for the upper tubular extension of said case and

the bearing 7 for center shaft 3, is mounted to be freely rockable upon right-angularly disposed pairs of trunnions 41 and 44 having bearings 43 and 45 in the cast annular yoke 42 and on the steel frame construction 46 bolted to the main base casting 27, and cushions 47 are provided between the bearings 43 and the steel frame 46 and between the yoke trunnion hubs and brackets case integral from the outside of the gear housing 40, as shown in dotted lines in Fig. 2.

Obviously the motor armature shaft rotates at the same speed as the center shaft 3 and the hollow screen or basket carried thereby, inasmuch as they are coupled together, the rotation being counterclockwise in top plan view although the direction of rotation is immaterial. By referring to Fig. 3 it will be noted that the arrangement of gearing provides that all gears rotate in the same direction and by such combinations of gear teeth as desired the tubular shaft 9 carrying the screw conveyor moves coaxially at a slower speed, the object of this differential speed being explained later. It should be understood however, that by rearranging the hand of the screw conveyor or changing the direction of rotation, it will be desirable to have the hollow screen rotate slower than the screw conveyor, which can, of course, be readily accomplished by gear teeth combinations.

The material to be treated enters by inclined chute 48 to the charging hopper 30 whence it falls by gravity through the annular space between the sleeve of said hopper and the tubular shaft 9 to the rapidly revolving loading plate 25. Centrifugal action then throws the material outwardly against the contracted upper portion of the conical end portion of the hollow screen, the liquid or moisture content then beginning to free itself from the material and passing through the filtering medium into the outer chamber located between the monitor case and the rotary screen. The material, freed in part from its liquid content, is retained on the inside of the conical end portion of the hollow screen and is evenly distributed thereon due to the annular frusto-conical space between the inner and outer circumferential surfaces of the frusto-conical screen lining 22, and end 24 of the conveyor wherein the material is free to slide around and to slide radially of said loading plate and gradually acquire the velocity of the screen basket and screw conveyor which it does not fully acquire until it reaches the screen basket and screw conveyor, when the screw conveyor will positively take hold of the material to rotate it.

The resultant of centrifugal force and gravity causes the material to slide down and around the incline of said conical end portion in said frusto-conical space, gradu-

ally picking up speed to the maximum and most efficient peripheral velocity along the vertical wall of the hollow screen. During the period of acceleration of speed down the incline of said conical end portion, the liquid content is gradually freeing itself from the material and passing through the screen. The angle of the conical end portion of the hollow screen is determined by the nature of the material being treated.

Due to the action of the loading plate 25, the frusto-conical end 24 of the screw conveyor, the frusto-conical end 16 of the hollow screen and the frusto-conical space therebetween, the material is evenly fed and distributed around the said frusto-conical end of the screen and so delivered to the hollow screen basket 15 to evenly load the same.

At the juncture of the vertical wall of the hollow screen and the incline of the conical end portion thereof, the screw conveyor positively moves the material downwardly, the dried material being discharged under the diffusion rim between the ribs or vanes of the bottom 8 communicating and coming in contact with the stationary incline of the main base casting 27, at a high tangential velocity, which is then retarded and the material deflected into a bin, hopper or other receptacle.

The liquid content or filtrate passing through the screens is collected within the annular case 26 and falls into the launder below and out through the openings provided for pipe connections.

It will be noted that the blades or flights of the screw conveyor incline upwardly, transversely and are provided with lateral surfaces having an arcuate angle wedge relative to the inner surface of the hollow screen thereby serving a two-fold purpose, first to facilitate the spreading of the material under the said flights, thereby permitting the liquid content to free itself more readily; and secondly in connection with the clearance space between the outer edges of the blades or flights and the inner circumferential surface of the hollow screen, causing the material to be wedged or forced outwardly of said lateral surfaces of the flights and through said clearance space to wipe clean the perforations or strainer holes of the screen.

Some problems demand washing, purging, or bleaching of the material after it is partially dried or freed of its liquid content, this being provided for by the introduction of a suitable agent through the pipe 49 which is stationary and discharges into an annular trough 50 cast integral with the screen bottom 8, whence through centrifugal force it climbs the vertical wall of said trough and passes through a perforation or perforations 51 of said wall to the interior of the hollow screw conveyor, the vertical wall of which it climbs

and sprays the agent through a perforation or perforations 52 of said screw conveyor between the blades of the said conveyor, upon the material.

5 Should it be desired to concentrate or separate the first run off of the liquid content of the material from the washing agent after passing through the screens, an annular shelf (not shown) could obviously be located 10 and secured to the inside of the monitor case 26 with suitable outlets.

Fig. 4 of the drawings shows a modification wherein the hollow screen 15a is slightly frusto-conical instead of being cylindrical, 15 as is also the screw conveyor 11a, the object of this being mainly to reduce the power required to force the material down the screen by the screw conveyor. An incidental advantage would be that the wedging of the material through the clearance space between the outer edges of the flights of the conveyer and the inner circumferential surface of the screen is accentuated to better wipe clean the strainer holes of the screen.

20 25 Due to the fact that the flights of the screw conveyor are of comparatively low incline, these flights are, for the clearance space stated, extended greatly in length to wipe clean all or practically all of the strainer holes of the screen.

30 Due to the wedging and spreading thin of the material through the clearance space referred to, the fluid treating medium or agent will be more intimately mixed with the material, and due to the comparatively low incline of the conveyor flights longitudinally and the consequent greater length thereof and of the clearance space, this intimate mixture will be very thorough.

35 40 Another modification of the invention is shown in Figures 5, 6, and 7, wherein while the right-angularly-disposed pairs of trunnions for the housing are to be retained, the cushions beneath the same are eliminated.

45 50 As shown, bottom 8a is somewhat modified from the main form and the center shaft 3a has lower bearings 55, whereof the inner portion of the raceway for the ball bearings and the tubular spacing sleeve 58, as well as the bottom 8a are clamped to the lower end of center shaft 3a against a shoulder by nut 63, a housing 56 being provided for said bearings and said nut and having a dust proof cover 57.

55 60 The housing 56 is provided with radial lugs 65, perforations of which are loosely engaged by the inner ends of tangential rods 59, the outer ends of said rods being pivoted to the lower flange of base 27a at 62, and said lugs 65 having lateral cups wherein fit elastic rubber cylinder cushions 60. The inner end of each rod 59 has a sleeve 64 loose thereon and which the bore of the related rubber cylinders 60 engage, the sleeve 64 being free to slide end- 65 wise and clamped at the ends by nuts 61 hav-

ing washers, this affording means for adjusting the plug of the center shafts. In this way outward thrust of the screen basket and screw conveyor under centrifugal force is resisted by the rubber cylinder cushions as shown in Figure 7.

70 75 The embodiment of the invention disclosed herein provides for a vertical axis apparatus, but it is within the spirit of the invention to apply the same to a horizontal axis apparatus or to one wherein the vertical axis is reversed from that disclosed, as will be obvious.

I claim:

1. In a centrifugal drier, a center shaft, a drier member carried thereby, a tubular shaft, a drier member carried thereby, and means for rotating said shafts and members differentially including mating pairs of gears, the members of each pair being eccentric with relation to each other and the outer gears of said pairs having a common carrier. 80 85

2. In a centrifugal drier, a center shaft, a drier member carried thereby, a tubular shaft, a drier member carried thereby, and means for rotating said shafts and members differentially including mating pairs of gears, the members of each pair being eccentric with relation to each other and the outer gears of said pairs having a common carrier provided with upper and lower tubular extensions 90 95 within the bores of which said shafts are eccentrically located, and a housing having bearings for said shafts and bearings eccentric of the first named bearings for said tubular extensions. 100

105 3. In a centrifugal drier, means for causing material as fed to be moved in one direction to gradually acquire speed and to be partly dried and evenly distributed as it is acquiring speed, and for causing the evenly distributed partly dried material to be moved farther in the same general direction at a substantially constant speed and to be completely dried comprising outer hollow rotatable screen sections one of which is a tapering extension of and joined directly and having an obtuse angle relation to the other, and an inner rotatable screw conveyor the body of which has a tapering extension spaced from said screen tapering extension. 110 115

4. In a centrifugal drier, an outer hollow rotatable screen, an inner hollow rotatable screw conveyor, means for causing material as fed to gradually acquire speed and be evenly distributed and partly dried and delivered to the space between said screen and said conveyor, and means for feeding a fluid treating medium between the flights at the end only of said conveyor to which the material is first fed to the evenly distributed partly dried fast moving material, said screen and said conveyor thereafter operating to completely dry the material. 120 125

5. In a centrifugal drier, an outer hollow rotatable screen, an inner hollow rotatable 130

- screw conveyor, means for causing material as fed to gradually acquire speed and be evenly distributed and partly dried and delivered to the space between the screen and the conveyor, and means for feeding a fluid treating medium between the flights at the end only of said conveyor to which the material is first fed to the evenly distributed partly dried fast moving material, including an annular
- 5 trough forming part of said screen, said conveyor having a perforation leading to the space between the flights at the inner end thereof, and a stationary pipe discharging into said trough.
- 10 6. In a centrifugal drier, an outer hollow rotatable screen, and an inner rotatable screw conveyor having flights provided with lateral surfaces facing in the direction in which the material is moving and having an acute-angle wedge relation to the inner surface of said screen to exert a wedging action upon the material being treated to force said material outwardly of said lateral surfaces towards said screen and through the clearance space between said screen and said conveyor to wipe clean the strainer holes of said screen.
- 15 7. In a centrifugal drier, an outer hollow rotatable screen, and an inner rotatable screw conveyor having upwardly and transversely inclined flights provided with lower lateral surfaces facing in the direction in which the material is moving and having an acute-angle wedge relation to the inner surface of said screen to exert a wedging action upon the material being treated to force said material outwardly of said lateral surfaces towards said screen and through the clearance space between the screen and the conveyor to wipe clean the strainer holes of said screen,
- 20 8. In a centrifugal drier, the upward incline of said flights facilitating the spreading of the material under the flights and the freeing of the liquid content of the material.
- 25 9. In a centrifugal drier, means for causing material as fed to be moved downwardly to gradually acquire speed and to be evenly distributed and partly dried as it is acquiring speed, and for causing the partly dried and evenly distributed material to be moved farther downwardly at a substantially constant speed, and to be completely dried, comprising outer hollow rotatable screen sections one of which is a tapering extension of and joined directly and having an obtuse angle relation
- 30 to the other, and an inner rotatable screw conveyor the body of which has a tapering extension spaced from said screen tapering extension, said space being of a length at least one half of that of the space between the conveyor and its screen section.
